UNITED STATES PATENT OFFICE.

PHILIP J. SMITH, OF LONG ISLAND CITY, AND JOHN F. McEVOY, OF BROOKLYN, NEW YORK.

CONVERTIBLE STREET-CAR.

SPECIFICATION forming part of Letters Patent No. 351,130, dated October 19, 1886.

Application filed July 29, 1886. Serial No. 209,445. (No model.)

To all whom it may concern:

Be it known that we, PHILIP J. SMITH, of Long Island City, in the county of Queens and State of New York, and JOHN F. McEVOY, of Brooklyn, in the county of Kings and State of New York, have invented a new and Improved Convertible Street-Car, of which the following is a full, clear, and exact description.

Our invention relates to a car whose sides 10 may be raised to a position at the top of the car and lowered therefrom to close the sides of the body of the car, so it can be readily converted into an open or closed car as the season and weather require.

15 The invention consists of the construction, arrangement, and combination of the parts of the car, all as hereinafter described and claimed.

Reference is to be had to the accompanying drawings, forming a part of this specification, 20 in which similar letters of reference indicate corresponding parts in all the figures.

Figure 1 is a side elevation of our new car as it appears with the sides elevated and the side steps lowered. Fig. 2 is an end elevation 25 of the same, showing the aisle seats in position. Fig. 3 is a transverse sectional elevation of the car, one side being closed, the other open. Fig. 4 is a perspective view of one of the aisle-seats folded, and Fig. 5 is a view of 30 the key for turning the shafts.

The bottom A, roof B, end walls, C, and platforms D of the car-body may be of the usual or of any approved construction. The platforms are provided at each side with a permanent step, D'. Framed into and between the end walls, C, are the open side frames, E E, each composed of a bottom bar, a, top bar, b, and uprights c c. The frames E are set in somewhat from the edges of the end walls, so the outer surfaces of the side pieces, F, when lowered will be flush, or nearly so, with the edges of the end walls. The upper bars, b, of the side frames, E, stand below the roof of the car, so that the side pieces, F, may be 40 carried over the top bars to occupy a horizontal or nearly horizontal position beneath the roof, as indicated in Fig. 3. The side pieces, F, are panels of suitable width and length formed with numerous windows, f, and they 45 are each attached at their ends to endless

chains G H for raising and lowering the side pieces. The endless chains G are passed over sprocket-wheels and pulleys secured upon the shafts J and K, the former journaled in the end walls near the roof, the latter journaled 55 in the end walls immediately over and in line with the top bar, b, on that side of the car. The endless chains H are passed over sprocket-wheels and pulleys secured upon the shafts L and M, the former journaled in the end walls 60 of the car a short distance from and a little below the shaft K, the latter immediately over and in line with the opposite top bar, b. The shafts J L are each provided at their ends with a ratchet-wheel, d, with which reverse-paws 65 e engage, and with which also the spurs s of the pawl S' of the key S engage for turning the shafts for raising and lowering the side pieces, F. The spaces between the upper edges of the side pieces, F, when lowered and the roof 70 of the car are closed by panels N, attached to the eaves of the roof, and these are hinged to swing outward, so they will not interfere with the side pieces, F, passing the pulleys of the shafts K M, in opening and closing the sides of 75 the car.

O O represent the continuous side steps of the car. These are each composed of a board, o, secured to a shaft, P, and a foot-piece or step, o', hinged to the board o, so that it is 80 adapted to stand at right angles to the board o, as shown at the right in Fig. 2, or folded flat against the board o, so as not to interfere with the latter being folded up to vertical position against the body of the car, as shown at 85 the left in Fig. 3.

The shafts P are provided at each end with a ratchet-wheel, h, with which the reverse-paws h' are adapted to engage for locking the shafts, and to these shafts the key S may be 90 applied for turning the shafts for raising and lowering the steps.

The seats Q Q in the car are permanent and transversely arranged, and do not reach to the center of the car, so that when only these seats 95 are used, as when the car is closed, there is a center aisle for passengers and the conductor to pass through the car.

When the car is used as an open car the aisle is closed by removable seats R, placed between 100

the opposite permanent seats Q, as shown clearly in Figs. 2 and 3. The seats R are adapted to be folded, as shown in Fig. 4, so that when not in use they may be carried in 5 small space. These seats are composed of three boards—viz., the leg portion e, the back e', and the seat portion e"—and these are hinged together, as shown in Fig. 4, so that the seat can be folded against one side of the back and 10 the leg portion against the other. The size of the seats R is made to exactly fit between the adjacent ends of the permanent seats Q, and thus when in place form continuous seats across the car.

15 The key S (shown in Fig. 5) is provided with the spring-pawl S', formed with side spurs, s, which are adapted to engage with the teeth of the ratchet-wheels upon the shafts. The end of the key is formed with an eye, s', to fit upon 20 the shaft loosely, so the key will turn easily on the shafts; and in order to relieve the hinges of strain when lowered for use, we secure to the edges of the boards o the rests t, and also to the edges of the boards o' the rests t', which act 25 to brace and support the boards o' when the steps are lowered to position for use.

Having thus fully described our invention, we claim as new and desire to secure by Letters Patent—

30 1. The body of the car constructed with the open side frames, E, of less height than the

end walls of the car, in combination with the shafts K M, journaled at the upper edges of the open frames E, the shafts L J, journaled at opposite sides of the center of the car, the endless chains G H, and the side pieces, F, attached to the chains, substantially as and for the purposes set forth. 35

2. The panels N, hinged to the roof of the car, in combination with the side pieces, F, 40 and frame for raising and lowering the same, substantially as described.

3. The side step, O, composed of the hinged boards o o', the board o being attached to the shaft P, substantially as described. 45

4. The key S, formed with an eye and provided with a spring-pawl, S', having the side spurs, s, substantially as described.

5. The board o of the hinged step, provided with rests t, in combination with the board o', 50 provided with the rests t', substantially as and for the purposes set forth.

6. The steps O, composed of the boards o o', hinged together, the board o being attached to the car by a rod on which it is adapted to 55 swing, substantially as described.

PHILIP J. SMITH.
JOHN F. McEVOY.
